UNITED STATES PATENT OFFICE.

JOHN NYE, OF MONTPELIER, OHIO.

WINDOW-SCREEN.

1,016,088.

Specification of Letters Patent. Patented Jan. 30, 1912.

Application filed March 22, 1911. Serial No. 616,243.

To all whom it may concern:

Be it known that I, JOHN NYE, a citizen of the United States, residing at Montpelier, in the county of Williams and State of Ohio, have invented certain new and useful Improvements in Window-Screens; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to improvements in roller window screens and it has for its object an improved construction of unitary nature which may be set up and removed or repaired with great facility and which may 20 be applied to windows without regard to the spacing or thickness of the sash frames, beading or blind stops.

The invention also presents sundry features of detail improvement, viz., an improvement in the construction and manner 25 of assemblage of the weather shield, an improvement in the connection between the sheet of screen netting and the spring wound roller, an improvement in the organization 30 of the arrangement as a whole and other features of detail improvement which will appear as the description proceeds.

35 Embodiments of the invention are illustrated in the accompanying drawings wherein—

Figure 1 is an elevation, partly in section of a screen construction conforming to the invention; Fig. 2 is a vertical section on the line 2—2 of Fig. 1; Fig. 3 is a horizontal section on the line 3—3 of Fig. 2; Fig. 4 is an enlarged vertical cross-section partly in elevation, on the line 4—4 of Fig. 2; Fig. 5 is a detail end elevation of the casing which incloses the spring roller; Fig. 6 is an enlarged section on the line 6—6 of Fig. 4 40 showing more particularly the connections between the spring roller and the sheet of screen netting; Fig. 7 is an elevation of the upper portion of the frame of the screen; Fig. 8 is a detail plan view of the connec- 45

tions between the spring roller and the sheet of screen netting; Fig. 9 is a detail sectional view showing a locking bolt and its adjuncts by which the screen is fixed at any desired elevation; Fig. 10 is a front elevation of the 55 same; Fig. 11 is an elevation, partly in section showing another form of the improved screen which is especially adapted for double windows; Fig. 12 is a vertical sectional view on the line 12—12 of Fig. 11; Fig. 13 60 is an enlarged horizontal sectional view on the line 13—13 of Fig. 12; Fig. 14 is a cross section through the spring roller.

Similar characters of reference designate corresponding parts throughout the several 65 views.

By reference to Figs. 1, 2 and 3, it will be seen that the screen and its adjuncts are assembled with relation to a rectangular frame which may be of suitably ornamental 70 character and which comprises an upper bar 1, side bars 2, and a lower bar 3.

The screen proper includes a spring wound roller, designated generally by the numeral 4, and a sheet of screen netting 5 75 which is associated with the roller 4. The roller is inclosed in a protecting casing which includes a weather guard 6, end plates 7, and a bottom plate 8. The weather guard 6 consists of a sheet metal wall which is 80 curved in cross-section as shown in Figs. 2 and 6, and which has its cross sectionally curved portion continued tangentially from its upper side, as at 9. The end plates 7 are fashioned to conformably fit within the 85 guard 6 and are secured within the end portions of said guard, as by screws 10. The bottom plate 8 is secured as by screws 11 to a flanged extension 12 of the guard 6, and the end portions of said bottom plate are 90 fitted in grooves which are formed in the end plates 7. The plate 8 is of less width than the space between the flange 12 and the upper frame bar 1 and thereby a slotted opening 13 is afforded through which 95 the screen netting 5 passes.

The spring roller 4, in its preferred embodiment comprises a hollow drum having blocks 14 and 14^a fixed within its end portions and having a block 15 fixed in a plane 100

near the block 14. A pin 16 projects axially from the block 14 and a pin 18 projects axially from the block 14^a. The pins 16 and 18 constitute trunnions for the roller and 5 have their bearings in the end plates 7. The pin 18 projects axially into the drum and has its inner end formed as a tenon to engage in an opening in the block 15. The pin 18 has fixed on its outer end a handle 20 10 which is provided with ratchet teeth 19 for engagement by a pawl 21 pivoted on the adjacent end plate 7. The pin 18 serves to center the operating spring 22, which is of the flat coil type and has its ends associated 15 with said rod and said drum, the said ends each having a hook formation and being engaged in recesses in the rod and the drum respectively. The pawl 21 engaging the teeth 19 serves to prevent backward turning 20 movement of the handle 19 and the pin 18 under the tension of the spring 22 but permits the handle 19 and therewith the pin 18 to be turned forwardly through a suitable extent whenever it is necessary to 25 increase the tension of the spring.

The preferred means of connecting the sheet of netting 5 and the roller 4 includes a bar 24 and links 25. The bar 24 is co-extensive with the width of the sheet of 30 netting and has an inturned flange which is clamped firmly upon the edge portion of the netting. The bar 24 is provided at equidistant points with openings 26 preferably having the shape of a crescent. Similar 35 openings, as 27, are formed at corresponding points of the hollow drum. Each link 25 which is of somewhat less width than either of the crescent shaped openings aforesaid has at its ends inturned hooks 28, which engage 40 over the straight edges of the respective openings 26 and 27. Three of these links are preferably employed.

The side bars 2 are provided at their upper ends with forwardly extending projections 29 which may be fashioned in 45 simulation of cornice work and may be parts of the ornamental features of the frame. The projections are bridged by a bar 30 and have their inner sides cut away so as to 50 afford grooves or recesses 31. The tangentially extended portion 9 of the weather guard 6 is of greater width than the guard so that, in effect, flanges 32 are provided which extend beyond the end plates 7. To 55 organize the screen and the frame the flanges 32 are fitted in the grooves 31 and the end plates 7 are secured to the side bars 2 as by screws 33 passing through extensions of said end plates.

60 The free edge portion of the screen netting which is drawn through the slotted opening 13 is provided with a bar 34, the ends of which are inturned as at 35 and clamped upon the netting. The end portions

35 of the bar 34 serve also as guides whereby 65 the movements of the sheet of screen netting may be straight and regular, and for this purpose work in grooves or recesses 36 which are formed in strips 37 that are attached to the side bars 2. 70

The bar 34 provides also for the attachment at the opposite side of the netting, of a bar 38 which is disposed between the side bars 2 of the frame and which carries at its ends sliding spring pressed bolts 39. 75 The escutcheon plates of these bolts are attached to the exposed vertical face of the bar 38 and the finger pieces by which the bolts are retracted or projected pass through bayonet slots 40 in these escutcheon plates 80 (Fig. 10). The side bars 2 each have their inner faces provided with a vertical row of openings 41 which are arranged at suitable intervals and are formed to receive the bolts 39. 85

For the purpose of excluding dust which might otherwise pass through the slotted opening 13, the plate 8 has attached to its under face a suitable strip 42 which extends partially across the opening 13 and with its 90 edge bears against the sheet of screen netting.

In use, the screen frame, comprising the bars 1, 2 and 3 and to which the weather guard with the inclosed spring roller and 95 sheet of netting has been fitted, is attached to the window casement or frame by screws or other suitable fastening. The entire screen is thus assembled in a unitary manner and its assemblage involves no modification whatever of the window frame and is entirely independent of the spacing or thickness of the sash beads. In case the window frame should be slightly out of plumb, as not infrequently occurs the screen frame 100 may be slightly "sprung" to meet the condition and the straight travel of the sheet of netting is at the same time, assured, since the particular connection between the netting and the roller allows of such side play 110 of the netting as may be necessary to insure its straight travel, regardless of the springing of the screen frame.

Not only is the entire arrangement capable of attachment to and removal from the 115 window frame in a unitary fashion but the weather guard and the spring roller and the netting are also capable of unitary attachment to and removal from the screen frame. The construction is therefore very readily 120 accessible for the purposes of renewal and repair and it may be attached to or removed from a window frame in the quickest and most convenient manner. It will be observed that the arrangement is altogether self contained; that is to say, that it embodies in 125 itself every element essential for its operation and that it does not necessitate the use

of structurally independent adjuncts which must be applied to the window frame, nor in fact any operations whatever in connection with the window frame except the attachment of the screen frame thereto.

The construction shown in Figs. 11, 12 and 13 is intended for use in connection with double windows and makes provision for duplicating the screens in a self contained organization. In this construction the casing which is provided by the weather guard 6, the bottom plate 8 and the end plates 7, has fitted therein a centrally arranged partition plate 43. The spring rollers are arranged at each side of this partition plate and their trunnions 16 are journaled therein. The window casing is shown as having an extended sill 44 which renders the use of the bar 3 unnecessary, the side bars 2 being imposed directly on this sill as shown in Fig. 12.

The modified construction includes also a centrally arranged vertical bar 45 which is associated with the bar 1 as by a rabbet joint 46 and which may be braced at the sill as by an angle plate 47. The bar 45 has its side faces formed with grooves or channels 36^a corresponding to and complementing the channels 36 aforesaid in the function of guiding the sheets of netting; and also with openings 41^a, corresponding to the openings 41 aforesaid.

The modified construction is in other respects similar to the construction already described.

Having fully described my invention, I claim:

1. A roller screen construction including a casing consisting of a weather guard, end and bottom plates secured thereto, a spring roller journaled in the end plates, a frame provided with recessed projections, the end plates being fastened to the frame and the weather guard having flanges at its ends which interfit the recesses of the projections and a sheet of screen netting connected to the roller and passing therefrom through the space between the bottom plate and the frame.

2. A roller screen construction including a casing consisting of a weather guard, end and bottom plates, a screen frame with which the casing is removably associated and which is adapted for attachment to a window frame, the side bars of the screen frame having openings in their opposed faces, a spring roller journaled in the end plates, a sheet of screen netting connected to the roller and passing therefrom through the space between the bottom plate and the frame, recessed guide strips secured to the side bars of the frame, a bar connected to the free end of the sheet of netting and having end extensions which work in the recesses of the

guide strips, a second bar also connected to the free end of the sheet of netting and locking bolts provided at the ends of the second bar for engagement in the openings in the side bars of the frame.

3. A roller screen construction including a casing consisting of a weather guard, end and bottom plates secured thereto, a spring roller journaled in the end plates, a screen frame provided with recessed projections, the end plates being fastened to the frame and the weather guard having flanges at its ends which interfit the recesses of the projections, the screen frame being adapted for attachment to a window frame, the side bars of the screen frame having openings in their opposed faces, a spring roller journaled in the end plates, a sheet of screen netting connected to the roller and passing therefrom through the space between the bottom plate and the frame, recessed guide strips secured to the side bars of the frame, a bar connected to the free end of the sheet of netting and having end extensions which work in the recesses of the guide strips, a second bar also connected to the free end of the sheet of netting and locking bolts provided at the ends of the second bar for engagement in the openings in the side bars of the frame.

4. A roller screen construction including a casing consisting of a weather guard, end and bottom plates, a screen frame with which the casing is removably associated and which is adapted for attachment to a window frame, guide strips associated with the side bars of the screen frame, a sheet of screen netting connected to the roller and passing through the space between the bottom plate and the frame, guide means provided at the free end of the sheet of netting for coöperation with said guide strips, and locking means also provided at the free end of the sheet of netting for coöperation with the side bars of the frame.

5. In a roller screen construction, a frame, a casing secured thereto and including a bottom plate which is spaced from the frame, a spring roller assembled in the casing, guide strips provided in the frame, a sheet of screen netting having at its free end guide means for coöperation with said strips, the sheet of netting passing through the space between the bottom plate and the frame, a bar associated with the other end of said sheet of netting and a link connection between said bar and said roller said link having a sidewise play on the roller and in said bar.

6. In a roller screen construction a frame, a casing secured thereto and including a bottom plate which is spaced from the frame, a spring roller assembled in the casing and including a hollow drum having a central opening, guide strips provided on

the frame, a sheet of screen netting having at its free end guide means for coöperation with said strips, the sheet of netting passing through the space between the bottom plate 5 and the frame, a bar associated with the other end of said sheet of netting and having an opening, and a link connecting the bar and the drum, the link having inturned

hooked ends for engagement in the openings aforesaid of both the drum and the bar. 10 In testimony whereof I affix my signature in presence of two witnesses.

JOHN NYE.
